UNITED STATES PATENT OFFICE

FRED MUGNAI, OF CHICAGO, ILLINOIS, ASSIGNOR TO ART SPECIALTY COMPANY, OF CHICAGO, ILLINOIS, A CORPORATION OF ILLINOIS

DESIGN FOR A BENCH END ARM OR THE LIKE

Application filed September 12, 1929. Serial No. 32,736. Term of patent 3½ years.

To all whom it may concern:

Be it known that I, FRED MUGNAI, a citizen of the United States, and a resident of Chicago, in the county of Cook and State of Illinois, have invented a new, original, and ornamental Design for Bench End Arm or the Like, of which the following is a specification, reference being had to the accompanying drawing, forming part thereof.

Fig. 1 is a side view of the arm showing my new design; and

Fig. 2 is an edge view of the arm.

I claim:

The ornamental design for a bench end arm or the like, as shown.

FRED MUGNAI.
